FRANKFURTER COOKER

George H. Frost, Ashland, Ohio, assignor to Westinghouse Electric Corporation, a corporation of Pennsylvania

Filed July 8, 1960, Ser. No. 61,282

Term of patent 14 years

(Cl. D81—10)

FIG. 1.

FIG. 2.

FIG. 3.

FIG. 4.

FIG. 5.

FIG. 1 is a perspective view of a frankfurter cooker, showing the new design;

FIG. 2 is a top plan view thereof;

FIG. 3 is a side elevational view thereof;

FIG. 4 is an end elevational view looking at the left end as viewed in FIGS. 1, 2 and 3; and;

FIG. 5 is an end elevational view looking at the right end as viewed in FIGS. 1, 2 and 3.

The side not shown in the drawing is similar in appearance to the side shown in FIG. 3.

The dominant features of my design reside in the portions shown in full lines.

I claim:

The ornamental design for a frankfurter cooker, substantially as shown and described.
